UNITED STATES PATENT OFFICE.

CHARLES BOOZE, OF BUFFALO, NEW YORK, ASSIGNOR TO M. H. BIRGE & SONS,
OF SAME PLACE.

DESIGN FOR WALL-PAPER.

SPECIFICATION forming part of Design No. 21,971, dated November 8, 1892.

Application filed October 10, 1892. Serial No. 448,455. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification, reference being had to the accompanying drawing, forming part thereof.

10 The leading feature of this design consists of an arrangement of ornamental scrolls connected to form ornamental panels with open wreaths and festoons of flowers and leaves hanging in the center of said panels, as shown 15 in the accompanying drawing. The ornamental scrolls are joined by small fleur-de-lis ornaments at the top and bottom and sides of said panels. A ribbon hangs from a fleur-

de-lis ornament at the top of the center panel, and from this ribbon is suspended an open 20 wreath and spray of flowers and leaves. The ornamental scrolls of the two adjoining center panels also form ornamental side panels containing festoons of flowers and leaves.

The design is printed in any desired color 25 or colors upon tinted paper of any desired color.

What I claim is—

The design for wall-paper herein shown and described. 30

Witness my hand this 7th day of October, 1892.

CHARLES BOOZE.
